UNITED STATES PATENT OFFICE

PERCY A. ROBBINS, OF HIGHLAND PARK, ILLINOIS

ORE SKIP AND THE LIKE

Application filed June 12, 1931. Serial No. 543,789.

This invention relates to skips, buckets or other containers for the conveyance or elevation of ore fines or other materials liable to stick or accumulate in the containers. In the art of mining, for example, ore is transported through vertical shafts in skips and, as the ore is usually damp or wet, fine particles of ore stick to and become compacted in the bottom of the skip. These fines accumulate until the capacity of the skip is seriously reduced. When this occurs the skips must be stopped and cleaned by pick-and-shovel men which is a costly operation and involves serious delays in the operation of the mine. My object therefore is to devise means for preventing such accumulations.

I attain my object by providing the skip with a flexible bottom lining including enclosed air pockets, which pockets are compressible and expansible to cause the break up of deposits forming on the lining. A certain amount of compression followed by expansion is caused by the alternate filling and emptying of the skip, but I prefer to subject them to alternate changes of air pressure whereby they may be alternately expanded and collapsed after the skip has been emptied of its readily dischargeable contents.

The changes of air pressure may be effected by alternately exhausting air from the pockets and readmitting air at atmospheric pressure, by alternately introducing air under pressure and thereafter reducing the pressure, or by alternately exhausting air from the pockets and admitting air at more than atmospheric pressure.

The invention is hereinafter more specifically described and is illustrated in the accompanying drawing in which

Fig. 1 is a side elevation, partly in section, of part of the skip elevating and dumping mechanism;

Fig. 2 a vertical section of a skip provided with a bottom lining constructed in accordance with my invention showing also its connection with the air conduit; and

Fig. 3 a perspective view, partly broken away, of the bottom lining.

In the drawing like numerals of reference

indicate corresponding parts in the different figures.

In Fig. 1 I show the arrangement of the elevating and dumping mechanism of a skip. The skip 1 is hinged at 2 on a bridle 3, which slides on a guide 4. When the skip is in the upright position it rests on a cross bar 5 carried by the bridle.

At the dumping point a roller 6 on the skip enters the grooved guides 7 and 8, which tip the skip in a known manner as shown.

The skip itself is of ordinary form, being rectangular in cross section, the bottom rounding into the sides. In the bottom is fitted the lining 9, which is shaped to fit the contours of the bottom and has the inner surfaces of its margins curved to meet the sides of the skip. This lining is made of flexible material, preferably rubber, and is formed with an air pocket or pockets preferably intercommunicating.

In a preferred form the lining is provided with a pocket 10 extending around it adjacent the margin and a plurality of pockets 11 in the bottom portion communicating with one another and the marginal pocket.

The precise construction, however, of the lining with its pockets may be considerably varied. The lining is secured in place by means of bolts 12 having their heads imbedded in the material of the lining.

In order that the air pressure within the pockets may be varied at the time of dumping, I provide a coupling spigot 13 at one side of the bottom, which communicates with the air pocket 10 and is adapted to enter a coupling socket 14, a washer 15 being provided to make an airtight joint. This socket is shown as connected to a cross head 16. Connected with the socket 14 is a conduit 17 connected with suitable means whereby the air pressure in the conduit may be varied. It is evident that by varying the air pressure in the conduit the air pockets 10 and 11 may be alternately extended and collapsed, thus scaling off any deposits which may have accumulated on the surface of the bottom lining. While this operation might take place while the cross head is stationary, it is customary after the skip has been turned up-side-down

to hoist it ten or fifteen feet higher to give the finer particles a chance to loosen and fall out.

I take advantage of this movement to control the means for varying the air pressure in the conduit 17. For this purpose I provide a four-way valve 18 of any ordinary type and provided with the connection 19 for connection with the conduit 17, the connection 20 leading to the atmosphere, the connection 21 for communication with a source of air under pressure, and the connection 22 for communication with exhaust apparatus. The valve is actuated through the medium of the crank arm 23 connected to the valve spindle, the connecting rod 24 connecting the crank 23 with a crank arm 25 fast to the spindle of a pulley 26. Over this pulley is passed a chain 27 provided at one end with a weight 28 and at the other end connected with the cross head 16. As the cross head rises and falls, the conduit 17 is alternately brought into communication with the different connections 20, 21 and 22 so that the air pressure therein is alternately negative, atmospheric and super-atmospheric. The alternation of pressures satisfactorily accomplishes the object of my invention and effectively loosens adhering ore masses from the surface of the bottom lining. It will be understood, of course, that if air under pressure is trapped in the air pockets, collapse and expansion of the air pockets would take place by the loading and unloading of the skip, but it is preferred to employ other means such as described to effect the desired movements of the surface of the bottom lining with which the ore contacts.

It will be noted that the shape and arrangement of the pockets is very effective for the intended purpose, as parts of the surface where accumulation is most likely to take place alternately presents a concave and a convex aspect as the air pressure in the pockets is changed.

What I claim as my invention is:

1. A skip provided with a flexible bottom lining having a closed air pocket formed therein, whereby the exposed surface of the lining is deformable by variations in external or internal pressure.

2. A skip provided with a flexible bottom lining having a plurality of closed air pockets formed therein, whereby the exposed surface of the lining is deformable by variations in external or internal pressure.

3. A skip provided with a flexible bottom lining having a plurality of intercommunicating closed air pockets formed therein, whereby the exposed surface of the lining is deformable by variations in external or internal pressure.

4. A skip provided with a flexible bottom lining of dished form having a closed pocket extending around it adjacent the margin;

and closed pockets in the bottom portion communicating with one another and the marginal pocket, whereby the exposed surface of the lining is deformable by variations in external or internal pressure.

5. A skip provided with a flexible bottom lining of dished form having a closed pocket extending around it adjacent the margin; closed pockets in the bottom portion communicating with one another and the marginal pocket, whereby the exposed surface of the lining is deformable by variations in external or internal pressure; and an air coupling member in communication with the air pocket in combination with an air conduit provided with a coupling member adapted to couple with the coupling member aforesaid, whereby the air pressure within the lining may be varied, by varying the air pressure in the air conduit, to deform the exposed surface of the lining.

Signed at Chicago, Ill., this 2nd day of June, 1931.

PERCY A. ROBBINS.
